CLAIM

The design for a privacy blanket for a nursing mother, as shown and described.

DESCRIPTION

FIG. 1 is a perspective view of a privacy blanket for a nursing mother, showing my new design in use, the partial broken line showing of a female figure being for illustrative purposes only;

FIG. 2 is a front elevational view shown open and spread flat, the rear being substantially identical.

The fabric insert below the shoulder band of the garment is understood to be of a sheer nature, and therefore substantially transparent.
